ELECTRIC ZINC-DISTILLING FURNACE AND CONDENSER.

1,265,973.

Specification of Letters Patent.

Patented May 14, 1918.

Application filed January 19, 1916. Serial No. 72,906.

To all whom it may concern:

Be it known that I, JOHN THOMSON, a citizen of the United States, and a resident of the borough of Manhattan, city of New York, county and State of New York, have invented certain new and useful Improvements in Electric Zinc-Distilling Furnaces and Condensers, of which the following is a specification, reference being made to the accompanying drawings, forming a part thereof.

This invention relates to the metallurgy of zinc having particular reference to the purification of impure spelter by the distillation and condensation thereof in an electric furnace, and the objects are to increase the rapidity and effectiveness, and decrease the cost, of such operations.

In the accompanying drawings which form a part of this specification there is represented a preferred mode of realizing the ends in view but the invention is not necessarily confined to the precise details shown in the drawings and described herein. In the said drawings Figure 1 is a vertical, transverse center section of the furnace and its condenser, taken as on the planes indicated by line A of Fig. 2 and lines A and A¹ of Fig. 3; Fig. 2 is a vertical longitudinal center section of the furnace, taken as on the planes indicated by line B of Figs. 1 and 3; Fig. 3 is a plan of the furnace and condenser, their covers being removed; this figure is a view taken as on the plane E of Fig. 1; Fig. 4 is a transverse section of the condenser, taken as on the planes indicated by lines C of Figs. 1 and 3; Fig. 5 is a detached, enlarged longitudinal section of a trapped tap for permitting the continuous flow of condensed metal and Fig. 6 is a transverse section of said tap, and is a view taken as on the plane indicated by line D.

The heating system of the furnace is comprised in a carbon resistor, F, formed of two slotted plates, 7, 8, producing a zig-zag electric circuit, attached by a connector, 9, to operate in series by electrification from right and left hand terminals 10, 11.

Beneath the resistor is a shallow trough or open tank, 12, which contains the bath of molten spelter, 13, supplied by a spout, 14, preferably located in the end of the furnace opposite from that in which the termi-

nals are set. A novel feature in this trough is that its end, under the spout, is depressed to form a sump, 15. The major portion of the bottom of the trough is provided with a rather sharp slope, 16, declined toward the sump, and it is designed to receive a shallow charge of fluid metal. A large emergency opening, 17, in the end-wall of the trough, is inclosed by a removable refractory, 18, having therein a small tap-hole, 19, located near to the bottom of the sump. One object of this construction is to permit lead or any metal of greater density and having a higher fuming temperature than zinc to precipitate and flow to and accumulate in the sump, from which, at intervals, it is drawn off through the tap hole, 19. Also, another object of the invention is to provide a construction whereby, when charging metal is delivered through the spout, plunging directly into the sump, the whole of the zinc in the trough will not be materially agitated. A prime advantage of the foregoing conditions is that little if any lead will be fumed irrespective of the length of time the furnace may be run. Moreover, as the quantity of metal contained in the shallow portion of the trough is relatively normal, it may at times be completely exhausted, in the form of fume, down to or even below the sump-level, as 20, when the latter can be entirely withdrawn. This is of particular advantage when changing from one class of spelter to another, as the residual loss is thereby minimized.

As the rising velocity of the fume from the bath toward the resistor is comparatively slow it becomes more or less super-heated. In order to eliminate some portion of this super-heat and yet to prevent a free upward escape of heat from the resistor itself, an overlying compound septum is provided formed by a lower series of refractory plates, 21, spaced to produce a plurality of central slits, 22, and above these plates is another series, 23, set closely together but leaving openings, 24, 24^a, at the end walls of the furnace. In this wise, there is formed a primary or resistor chamber, H, an intermediary septum chamber, I, and an upper or fume chamber J, from whence a centrally located port, 25, leads to the condenser. The consequence of this arrange-

ment is that the fume passes up through the slots of the lower septum, deflects right and left, and flows horizontally through the septum chamber, as arrows *a*, rises through the 5 end openings of the upper septum, as arrows *b*, flowing along the end walls of the furnace and thence along its side walls and the upper surface of the upper septum and also the roof, finally reaching the port, as arrows *c*.
10 The result is that a large portion of the upwardly radiated heat from the resistor is conserved, but a considerable portion of the heat necessarily imparted to the fume is transferred to the upper portions of the 15 furnace thereby reducing the duty to be imposed upon the condenser. The extent of this prior cooling may be considerably controlled at the roof by employing a primary layer of carbon slabs, 26, having freely 20 set thereon a layer or layers of heat insulating bricks, 27, which may be removed or added to permitting a more or less free radiation of heat; which will be largely that contained in and given up by 25 the fume. Thus, while the temperature of the fume when in the resistor chamber may be, say, 1,350° C., it is feasible to diminish it by some 200° or 300°, which would be about as low as would be desirable for condensation to liquid metal, at its entry to the 30 condenser. Obviously, in such circumstances, the capacity of a condenser of any given dimensions would be substantially enhanced. Or, stated conversely, the temperature of the resistor may be carried higher, with thermal advantage, than would otherwise be permissible.

In the first "blowing-in" of a zinc distilling furnace, considerable losses are incurred through absorption of zinc in the 40 brick-work, particularly by porous heat insulating bricks. This objection can be largely minimized by incasing the ends, sides and bottom of the refractory bricks, 28, 45 which form the general furnace chamber, with thin strips of metal or asbestos-board, as 29. By simply observing that this barrier-casing, which can be made with few or even no joints, is sufficiently protected as 50 not to fuse or be decomposed, a complete seal is interposed between the inner courses of dense refractory bricks and outer courses of porous heat insulating bricks and the primary loss of zinc and time becomes nominal.

55 The coördinating condensing feature of the invention will now be described. With the complete temperature control and the high thermal efficiency obtainable in an electric furnace of the type herein denoted, it 60 is feasible to precipitate, in the sump, nearly all of the lead and iron usually contained in low grade spelter; but with respect to cadmium, which is frequently present in spelter, such a precipitation either does not occur, or 65 at the best to a very limited extent. The

reason for this is that the normal boiling point of cadmium may be taken to be 780° C., as compared 930° for zinc. Hence, in general terms, cadmium will both boil and begin to condense at a temperature of 150° 70 C., less than zinc. In practice, the fume of both metals may rise and commingle together; and so, too, they may condense together, that is when the condensing temperature of the cadmium will have been 75 reached. The foregoing also applies to other metals; as, for example mercury. Advantage is taken of these physical properties to effect a more or less complete separation, or segregation, of the mixed or alloyed metals by, as it may be termed, a system of fractional condensation.

Thus, the condenser, *P*, of a type previously developed and illustrated by the present applicant, has a throat, 30, connecting it 85 to the furnace port which receives the out-flowing fume at some temperature sensibly higher than the condensing point of zinc. Within the condenser are a series of staggered baffle-plates, 30^a, shorter than the 90 width of the casing, thereby forming end-spaces, the fume flowing in a sinuous, horizontal plane along and between the plates and around their ends, as shown by arrows *i*. The condensed metal is collected in the 95 bottom of the casing, forming a bath as 31, in which the lower portions of the baffle plates are immersed, and this bath is maintained at a constant depth by means to be later described. Toward the outer end of 100 the condenser two plates are shown, 32, 32^a, which are the full width of the casing except where upper portions of the ends are cut away to form spaces, as 33, 34. Thus, all of the metal to the right hand side of plate 32 105 is segregated in a common bath; but any metal condensed in the space *R*, or in the space *S*, between the rear plates, is separately contained therein and is not in communication with the larger forward section. 110 In other words, both fume and metal flow around the ends of the forward plates, while at the rear plates the fume only is free to flow, the liquid metal being confined. Now, by a proper control of the temperature of 115 the condenser, as by its rate of heat radiation to atmosphere, whereby the fall of the temperature from the throat to the rear will be in a progressive ratio, as by the employment of graduated insulation, indicated in 120 dotted lines, *z*, Fig. 1, all or a major portion of the zinc-fume can be condensed when the zone indicated by the line *C* will have been reached and whereat the temperature will perhaps be about 750° to 800° C. In 125 these circumstances, the cadmium will still be a vapor, continuing however to flow along as indicated by arrows *w*, and the temperature progressively falling to, say, 500° to 450°, the cadmium will then condense and be 130

entrained in one or the other or both of the rear spaces, R, S. The foregoing description of fractional condensation contemplates an operation under ideal conditions. In practice, owing to pulsations in the flow of fume, atmospheric conditions affecting the rate of heat radiation, etc., the zone of demarcation will fluctuate correspondingly, whereby a certain proportion of cadmium 5 may be condensed with the zinc in the main forward compartment, or zinc may be condensed with the cadmium in one or both of the rear compartments. For usual commercial purposes, however, even such a result is satisfactory, for the reason that the objectionable quantity of cadmium in spelter does not exceed, ordinarily, from $\frac{1}{10}$ to $\frac{1}{5}$ of one per cent. and an elimination of the major portion thereof is adequate.

20 To obtain the very best results in condensation such as a high rate of precipitation, uniform temperature and with a minimum of attention on the part of the operator, the reserve bath or baths, should be maintained 25 at a constant depth; which means that the zinc should flow out as rapidly as it is condensed. To accomplish this, the essential conditions involved are that the means employed must be entirely automatic; that absolutely no air shall be permitted to enter; 30 that the flow shall be free and ample and that there shall be no possibility of "freezing." These conditions have been fully met and the desired end realized by the simple device 35 shown in the drawings, particularly Figs. 5 and 6, consisting of a cylindrical plug, 40, having an axial bore, 41, but with a dead end, 41^a. Near to the dead-end is a vertical transverse opening, 42, passing 40 through the cylinder and connecting with the horizontal axial bore. This plug is inserted in a wall of the condenser, so that the vertical opening shall face downwardly; the location being such that the inner intersection 45 of the said vertical opening with the horizontal axial bore shall be the height, or depth, at which the bath, as 43, is to be maintained. Whenever the level of the bath rises above the aforesaid plane, the liquid zinc 50 immediately runs out. If the fixed plane is again reached, the flow of zinc ceases, but as the vertical opening is filled, no air can enter the condensing chamber. Moreover, as the lower surface of the plug is immersed 55 in the bath the metal in the vertical opening cannot "freeze" or become in the slightest degree sluggish. To facilitate a rapid flow, the axial bore is shown tapered; but the same effect can be obtained by setting the 60 plug at a slope.

As shown in Figs. 1 and 3, the condenser is provided with three of these taps, that on the right hand side serving to automatically and continuously draw off zinc while the 65 two others, being in compartments R and S,

evacuate the accumulation from each separately. The tap or taps, may be of any desired length, as denoted in dotted outline t, Fig. 3. No extra precaution or attendance is required other than to provide suitable 70 extraneous receptacles; which should preferably be adequately heated to maintain the metal in a liquid state until poured into molds. It is to be particularly observed that once the bath is established the draft is 75 thereafter entirely from near its surface; there is no disturbance of the entire volume of reserve metal; the rate of flow along the surface of the bath toward the tap is exceedingly slow; hence, in an operation of 80 long duration, there is an ideal opportunity for an accumulation along the bottom of the condenser, by density displacement, of the heavier metals, as cadmium out of zinc, or lead out of zinc, or cadmium-lead out of 85 zinc, limited of course, by the extent to which one of these metals may be dissolved in another. In any event, by maintaining a "dead" bath the opportunity for precipitation of metals having a greater density 90 than zinc is compounded; firstly, to a major extent, in the trough-sump and, secondly, to a minor extent, in the condenser itself.

What I claim is:

1. An electric furnace for distilling spelter having a condenser in which there is a plurality of staggered plates around the ends of a portion of which both fume and condensed metal may flow but around another portion of which only fume can flow. 95

2. An electric furnace for distilling spelter having a condenser connected thereto which condenser has a plurality of staggered plates between and around the ends of which condensed metal is contained as a 100 main or common bath, and another plate or plates around the end or ends of which fume may flow but whereby metal condensed thereat is separated from the main bath. 105

3. An electric furnace for distilling spelter contaminated with metal of greater density than zinc, which furnace has an attached condenser that is provided with means for constantly withdrawing metal, as and when condensed, from the upper portion 110 of a bath, or baths, contained within the said condenser. 115

4. In an electric furnace for distilling spelter contaminated with another metal, or metals, a condenser having a plurality of 120 automatic trapped taps for withdrawing the condensed metal from different vertical zones of said condenser.

5. An electric furnace for distilling spelter having a condenser attached thereto, 125 which condenser is provided with a trapped tap in which the sealing end is immersed in a bath contained within said condenser.

6. A liquid metal condenser having a 130 trapped tap formed by a plug having a hori-

zontal axial bore terminating at a dead-end and a vertical connecting opening, the latter being set to face downwardly and be immersed beneath the surface of a bath contained within the condenser.

7. A liquid metal condenser having a tubular trapped tap for withdrawing metal as and when condensed from any desired

portion, but near to the surface, of a bath contained within the condenser.

This specification signed and witnessed this 18th day of January, A. D. 1916.

JOHN THOMSON.
